UNITED STATES PATENT OFFICE.

IRA E. CUMPSTON AND LISLE N. PYZER, OF TRYON, NEBRASKA.

STOCK GUARD.

Application filed December 20, 1926. Serial No. 155,941.

This invention relates to a stock guard for roads running through or into a stock yard, and has for its primary object to prevent the passage of the stock from the enclosure, but at the same time to permit automobiles or other power vehicles to pass through the enclosure at will.

A further and important object is to provide a stock guard wherein the use of gates and bars are unnecessary for keeping stock from passing through the opening in the fence, and through which the road passes.

A still further and important object is to provide a stock guard of this character that is extremely simple of construction, inexpensive of manufacture, and one that may be installed at moderate expenditure.

With the foregoing and other objects in view that will become apparent as the nature of the invention is better understood, the same comprising the novel form, combination, and arrangement of parts herein-after more fully described, shown in the accompanying drawing and claimed.

In the drawings wherein like reference characters indicate corresponding parts throughout the several views:

Figure 1 is a top plan view of a stock guard constructed in accordance with the present invention.

Figure 2 is a section taken through the road passing between spaced fence sections between which the present stock guard is also arranged, the same being disclosed in end elevation.

Figure 3 is a side elevation of the stock guard.

Figure 4 is a fragmentary longitudinal section through one side thereof, and

Figure 5 is a fragmentary transverse section through the similar side thereof.

Now having particular reference to the drawings our stock guard consists of two similar constructed track units 5—5 that are interconnected in spaced parallel relation at their opposite ends by boards 6—6 and 7—7, which boards are disposed beneath and at the extreme ends of the track units, respectively, as clearly disclosed in Figures 3 and 4. Each track unit consists of a pair of spaced parallel boards 8—8 that are interconnected inwardly of their opposite ends by cross boards 9—9, the upper edges of which terminate beneath the upper edges of the side members 8—8 as clearly indicated in Figure 4. The opposed faces of the par-

allel side boards 8—8 are provided at predetermined spaced points with registering circular sockets 10—10 for receiving the opposite ends of pipe sections 11 that will support the wheels of a vehicle passing over the track unit, but by reason of their spaced relation will prevent animals walking thereacross.

Extending through certain of the pipe sections in spaced relation with the opposite ends of the track ways are elongated rods 12—12 that are headed at certain ends and threaded at other ends and said threaded ends receive locking nuts 13 in order that the side boards 8—8 are rigidly and further interconnected so as to prevent the expansion of the same and the consequent detachment of the pipe sections with respect thereto.

Extending entirely between the outer boards 8 of the track units 5—5 adjacent their opposite ends are relatively elongated pipe sections 14—14, that pass through openings provided in the innermost side boards 8 and engage at their extreme outer ends within sockets formed in the inner faces of the outermost boards similar to the sockets 10 previously described, these pipe sections being mainly for the purpose of preventing any inward movement of the track unit with respect to each other.

Further there is provided between the center of the guard a pipe section 15 through which and the side boards 8—8 of each track unit is extended a relatively elongated rod 16 headed at one end and threaded at its other for receiving at said threaded end a locking nut 17, it being understood that the rod 16 extends through registering openings in the side boards of the track units.

The upper edges of the side boards of said track units extend somewhat above the end boards 7—7, and insomuch as the guard is to be disposed flush with the ground surface as in Figure 2, that is the upper edges of the side boards of the track way will be flush with the ground surface, the ends of the side boards 8—8 are tapered at their inner sides as at 18 so as to prevent the engagement of any sharp corners with the tires of an automobile that may be passing across the guard.

Furthermore, it is our purpose to form a pit A in the ground directly beneath the center of the guard so that animals will be frightened from attempting to cross the road

between the track units 5—5. Also as disclosed in Figure 2, the guard is to be disposed directly within a space in the fence line A through which space passes a road 5 which is an obvious and well known expedient requiring no specific description.

In view of the foregoing description when considered in conjunction with the accompanying drawings it will at once be apparent that we have provided a highly novel, 10 simple and efficient stock guard that is well adapted for all the purposes heretofore designated, and even though we have herein shown and described the invention as consisting of certain detail structural elements, it 15 is nevertheless to be understood that minor changes may be made therein without affecting the spirit and scope of the appended claims.

Having thus described the invention, what 20 we claim as new is:—

1. In a stock guard of the character described, a pair of parallel track units, each of which consists of a pair of side boards 25 having spaced registering sockets in opposed surfaces, bars securely arranged at their ends in registering sockets, elongated bars extend-

ing through the units adjacent opposite ends thereof for preventing inward movement of the units with respect to each other, a bar 30 arranged between the units at the center thereof, and an elongated locking rod extending through said units and said bar for preventing outward movement of the units with respect to each other. 35

2. In a stock guard of the class described, a pair of parallel track units each of which consists of a pair of side boards having spaced registering sockets formed in the inner opposed faces thereof, tubular bars 40 having their respective ends fitted within the respective pairs of registering sockets, bolts extending through certain of the tubular members and the side boards of each unit for securing the parts in assembled relation, means for preventing the inward movement 45 of the units with respect to each other, and additional means for preventing the outward movement of the units with respect to each other. 50

In testimony whereof we affix our signatures.

IRA E. CUMPSTON.
LISLE N. PYZER.
